UNITED STATES PATENT OFFICE.

EDWARD CRAIG, OF ST. JOSEPH, MICHIGAN, ASSIGNOR TO SARANAC MACHINE CO., OF ST. JOSEPH, MICHIGAN, A CORPORATION OF MICHIGAN.

BERRY-BASKET MACHINE.

1,132,564.

Specification of Letters Patent. Patented Mar. 23, 1915.

Application filed December 9, 1909. Serial No. 532,199.

To all whom it may concern:

Be it known that I, EDWARD CRAIG, a citizen of the United States of America, and resident of St. Joseph, Berrien county, Michigan, have invented a certain new and useful Improvement in Berry-Basket Machines, of which the following is a specification.

My invention relates to machinery for making berry baskets or similar articles.

It relates to stapling machinery for various purposes.

More specifically considered, it relates to machinery for making small receptacles, such as square baskets of the kind that are commonly used for berries and small fruits.

The object of my invention is to provide an improved construction and mode of operation whereby a plurality of forms, each adapted to rotate about its own individual axis, are mounted to revolve about a common axis, so that the baskets or other articles on the forms may be successively brought into position to be stapled, and whereby the materials for other baskets or articles may be assembled in position on one or more forms while another form is being rotated about its individual axis to bring the different sides of the basket thereon into position to be stapled, the forms being successively presented to the stapling mechanism, by bodily motion only in one direction about their common axis, and each form having rotary motion while coöperating with the stapler.

For certain broader purposes of my invention, such, for example, as the successive presentation of the different sides of a form to the stapler, which stapler works at an angle to the axis of the form, and the substitution of one form for another, whereby one form may be loading while another is coöperating with the stapler, the forms do not necessarily revolve only in one direction, but could move back and forth, in any suitable manner, without departing from the spirit of my invention.

To these and other useful ends, whereby the cost of production of baskets or other articles may be reduced, or rendered more satisfactory, my invention consists in matters hereinafter set forth and claimed.

In the accompanying drawings, Figure 1 is a plan of a basket or other stapling ma-

chine embodying the principles of my invention. Fig. 2 is a vertical section on line 2-2 in Fig. 1. Fig. 3 is a vertical section on line 3-3 in Fig. 2. Fig. 4 is a detail section on line 4-4 in Fig. 1. Fig. 5 is a detail section on line 5-5 in Fig. 1. Fig. 6 is a detail vertical section on line 6-6 in Fig. 2. Fig. 7 is a fragmentary sectional view of the locking and tripping devices for the rotary form carrier. Fig. 8 is a similar view, showing the said devices in another position. Fig. 9 is a detail perspective view of one of the said tripping elements. Fig. 10 is a vertical section on line 10-10 in Fig. 1. Fig. 11 is a horizontal section on line 11-11 in Fig. 10. Fig. 12 is a perspective of the feed ratchet and tripping plate of one of the forms. Fig. 13 is a perspective of a tripping element shown in Figs. 7 and 8. Fig. 14 is a perspective of one of the forms. Figs. 15 and 16 shows another form of mechanism for tripping the clutch when the basket is finished.

As thus illustrated, my invention comprises an upright pedestal A having a rotary form carrier B at the upper end thereof. This carrier rotates about a vertical axis b, and is provided with forms C on the upper surface thereof. These forms are held yieldingly against rotation by the spring controlled fingers or arms c that bear on their sides. Each form has a plate c' provided with a tripping notch c² and a feed ratchet wheel c³. Each form has an individual vertical axis c⁴. The carrier B is rotated by hand, so as to successively bring the forms C in front of the stapling head D, which latter comprises two staplers arranged to drive the staples obliquely to the circumference of the form, as shown in Figs. 5 and 6. This stapling mechanism may be of any suitable form or construction, and as staplers are well known no detailed description of this one is necessary. The multiple stapler head thus arranged at an angle to the axis of the form carrier B, and to the axes of the forms C, is operated by a rod d which connects with a crank plate d' on the drive shaft E. A feed pawl in the form of a hook d² is actuated by the stapler head to operate the feed ratchet wheel c³ of each form. When the head D moves back the hook d² engages a tooth of the ratchet wheel c³ and rotates the form—that is, gives it a

quarter turn. A spring d^3 controls the said hook, to hold it to its work, and a guide d^4 keeps the hook in the right path of motion. The wire feed F is operated by a pitman f, which latter is operated by an eccentric on the shaft E. This feeds the wire through tubes f' to the multiple driver stapler D, in the well known manner.

The carrier B has a hole G under each form, adapted to register with the notches c². A locking rod g reciprocates up and down with the sleeve g', which latter is connected by a spring g² with the under side of the frame a. The lower end of this rod g is suitably connected with the lever g³, which latter is pivoted at g⁴. This lever is in turn connected by a rod g⁵ with the foot lever g⁶. The upper end of the rod g is adapted to slide on the lower surface of each plate c', and to engage the notches c². The form in front of the stapler is rotated until the notch c² engages the rod g, and then the machine stops. During the rotation of the form the carrier is locked by the engagement of the hole G with the rod g.

Any suitable means may be employed for causing the upward motion of the rod g, when it registers with a notch c², to stop the machine. As indicated in Figs. 2, 7, 8, 9 and 13, the sleeve g' has a hook or tripping element H pivoted thereto, and controlled by a spring h. A rock shaft h' is mounted in suitable bearings and provided with a coöperating tripping element h², which latter is controlled by a spring h³. Another arm h⁴ on this rock shaft is adapted to engage and operate the clutch pin h⁵. As this particular clutch is no part of my invention, detailed description is not necessary. It may be any suitable or known form of clutch on the shaft E. While the rod g is held down by the plate c', the elements H and h² are engaged as shown in Fig. 2; but when the said rod moves upward through a notch c², then the element H slips over the element h², as shown in Fig. 8, thus allowing the spring h³ to pull the arm h⁴ into engagement with the pin h⁵, which opens the clutch and stops the machine. When the rod g is pulled down the element H slips off from the element h², as shown in Fig. 7. Then when the rod g is released by the foot, and allowed to rise, the element H wedges back of the element h², as shown in Fig. 2, thus again closing the clutch and starting the machine. Instead of this arrangement, the mechanism shown in Figs. 15 and 16 may be used for starting and automatically stopping the machine. In this case the arm I, which corresponds to the element h, is connected to be operated by the bell crank i. This bell crank lever has a hook-like end i' adapted to be engaged by the part i² pivoted on the sleeve g'. This part i² is held down by a spring i³, so that it can pass the hook i

when the rod g moves downward. The part i² rests against the hook i' to keep the lever i raised, and to keep the clutch closed and the machine going. When the rod g rises, as explained, the part i² passes out of engagement with the part i', and allows the lever i to fall and open the clutch. The usual belt pulley J and clutch j are provided on the end of the shaft E for operating and controlling the machine.

Preferably, the staplers are supported on an arch K, as shown in Fig. 6.

The operation is as follows: The operator places materials on the forms C. Then the carrier B is rotated to bring one of the loaded forms opposite the staplers, the rod g having been depressed by the foot lever. Then the clutch j is operated to start the machine. The staplers operate until the four sides of the basket have been stapled, and then the rod g engages the notch c². This stops the machine; and the operator then depresses the foot lever and turns the carrier B to bring another form into position. As soon as the rod engages another hole G the machine automatically starts operating again. Thus while one basket is being stapled the operator is loading the other form.

So far as the feature of the staplers arranged to work at an angle to the axis of the form is concerned, the said form need not revolve in one direction only, but may, by suitable arrangement, travel back and forth. The carrier B can rotate in either direction, to suit the convenience of the operator.

What I claim as my invention is:

1. In a machine for making baskets or other articles, a plurality of forms, an axis about which the forms revolve, an individual axis for each form, means connecting all of said axes, a stapler arranged at an angle to said axes, adapted to coöperate with said forms, disposed in such manner that the staples are driven at an angle to the common axis, each form rotatable about its axis to successively present the different sides thereof to said stapler, means for automatically stopping the bodily motion of the forms, to permit each form to rotate in front of said stapler, and means for rotating the forms one at a time.

2. In a machine of the class described, a plurality of forms, means for moving the forms bodily, arranged to maintain the said axes in proper relation to each other, an individual axis for each form, a stapler arranged at an angle to said axes, adapted to coöperate with said forms, disposed in such manner that the staples are driven at an angle to the direction of travel of said forms at the stapling point, each form rotatable about its axis to successively present the different sides thereof to said stapler, means for

automatically stopping the bodily motion of the forms, to permit each form to rotate in front of said stapler, and means for rotating the forms one at a time.

5 3. In a machine of the class described, a rotary carrier, rotary forms mounted on said carrier, means for locking the carrier against rotation; means for rotating a form while the carrier is locked, a stapler coöperating with the forms, means for automatically stopping the stapler when the form has made a complete rotation, means for automatically stopping the bodily motion of the forms, to permit each form to rotate in front of said stapler, and means for rotating the forms one at a time.

10 4. The combination of a rotary carrier, rotary forms thereon, means for stapling the materials carried on the forms, means for locking the carrier, means for rotating the forms successively, whenever one is opposite the stapling means, devices for preventing rotation of the forms before they are brought into position before the stapling means, and means for automatically stopping the stapling means, as set forth.

15 5. In a stapling machine, a series of forms mounted to revolve around a common axis, so that each form may make one or more complete revolutions about said axis, each form having an individual axis about which it rotates, means for rotating the forms one at a time, and stapling mechanism coöperating with said forms successively, the axis 20 of each form being at an angle to the direction of insertion of the staples while co-operating with said mechanism, in combination with means for automatically stopping the bodily motion of said forms, serving 25 also to start the operation of said stapler.

40 6. In a stapling machine, a plurality of forms mounted to revolve about a common axis, in either direction, so that each form may make one or more complete revolutions around said axis, in either direction, and a stationary stapler arranged to coöperate with said forms successively, said stapler being arranged outside of the orbit of said forms, in combination with means for automatically stopping the bodily motion of said forms, serving also to start the operation of said stapler.

45 7. In a stapling machine, a plurality of forms each having a notch, a form carrier having a hole corresponding to each notch, and a locking rod adapted to work successively in said holes and engage said notches.

50 8. In a machine for making baskets or other articles, a rotary form, a stapler, a ratchet on the form, and a pawl on the stapler for operating said ratchet to rotate the form, the said rotation being intermittent and without disturbing the axis thereof, means for shifting the form bodily, and means for automatically starting the opera-

tion of said stapler upon the cessation of the bodily motion of said form in operative position.

5 9. In a machine for making baskets or other articles, a plurality of forms, an axis about which the forms revolve, an individual axis for each form, and a stapler arranged at an angle to said axes, arranged to coöperate with said forms, and means controlled by the bodily motion of the forms to automatically start the machine.

10 10. In a machine of the class described, a plurality of forms, means for moving the forms bodily, an individual axis for each form, a stapler arranged at an angle to said axes, to coöperate with said forms, and means controlled by the bodily motion of the forms to automatically start the machine.

15 11. In a stapling machine, a series of forms mounted to revolve around a common axis, so that each form may make one or more complete revolutions about said axis, each form having an axis about which it rotates, stapling mechanism arranged to coöperate with said forms successively, and means controlled by the bodily motion of the forms to automatically start the machine.

20 12. In a stapling machine, a plurality of forms mounted to revolve about a common axis, in either direction, so that each form may make one or more complete revolutions around said axis, a stationary stapler arranged to coöperate with said forms successively, and means controlled by the bodily motion of the forms to automatically start the machine.

25 13. In a machine for making baskets or other articles, a plurality of forms, an axis about which the forms revolve, an individual axis for each form, a stapler arranged at an angle to each axis, to coöperate with said form, means controlled by the bodily motion of the forms to automatically start the machine, and means controlled by the individual rotation of each form to automatically stop the machine.

30 14. In a machine of the class described, a plurality of forms, means for moving the forms bodily, an individual axis for each form, a stapler arranged at an angle to said axes, to coöperate with said forms, means controlled by the bodily motion of the forms to automatically start the machine, and means controlled by the individual rotation of each form to automatically stop the machine.

35 15. In a stapling machine, a series of forms mounted to revolve around a common axis, so that each form may make one or more complete revolutions about said axis, each form having an axis about which it rotates, stapling mechanism arranged to coöperate with said forms successively, means

controlled by the bodily motion of the forms to automatically start the machine, and means controlled by the individual rotation of each form to automatically stop the machine.

16. In a stapling machine, a plurality of forms mounted to revolve about a common axis, in either direction, so that each form may make one or more complete revolutions around said axis, a stationary stapler arranged to coöperate with said forms successively, means controlled by the bodily motion of the forms to automatically start the machine, and means controlled by the individual rotation of each form to automatically stop the machine.
17. In a machine for making baskets or other articles, a plurality of forms, an axis about which the forms revolve, an individual axis for each form, a stapler arranged at an angle to said axes to coöperate with said forms, and means governed by the rotation of each form to automatically stop the driving of staples, and controlled by the bodily motion of the forms to automatically start the machine.
18. In a machine of the class described, a plurality of forms, means for moving the forms bodily, an individual axis for each form, a stapler arranged at an angle to said axes to coöperate with said forms, and means governed by the rotation of each form to automatically stop the driving of staples, and controlled by the bodily motion of the forms to automatically start the machine.
19. In a stapling machine, a series of forms mounted to revolve around a common axis, so that each form may make one or

more complete revolutions about said axis, 40 each form having an axis about which it rotates, stapling mechanism arranged to coöperate with said forms successively, and means governed by the rotation of each form to automatically stop the driving of 45 staples, and controlled by the bodily motion of the forms to automatically start the machine.

20. In a stapling machine, a plurality of forms mounted to revolve about a common 50 axis, in either direction, so that each form may make one or more complete revolutions around said axis, a stationary stapler arranged to coöperate with said forms successively, and means governed by the rotation 55 of each form to automatically stop the driving of staples, and controlled by the bodily motion of the forms to automatically start the machine.

21. A stapling machine comprising a ro- 60 tary and bodily movable form, and means for automatically starting the stapling operation, controlled by the bodily motion of said form.

22. A stapling machine comprising a ro- 65 tary form, means for stopping the rotation of the form, serving also to stop the stapling operation, and means for automatically starting the machine, controlled by bodily movement of the form to operative 70 position.

Signed by me at St. Joseph, Mich., this 19 day of November, 1909.

EDWARD CRAIG.
